METHOD OF CONSTRUCTING SEA WALLS

Application filed December 10, 1928. Serial No. 324,832.

This invention relates to methods of building sea walls and more particularly to walls including a plurality of heavy blocks of concrete or other suitable moldable material and piles arranged to guide them into and maintain them in position and to methods of producing such structures.

In building sea walls, bulkheads, breakwaters and the like in which members such as piles are fixed substantially in parallel arrangement and with their axes in the same general plane and blocks are lowered between them and guided into position, it is difficult if not entirely impracticable to obtain exact spacing of the guiding members, especially when these members are to be as truly parallel as possible and driven to a considerable depth and in some cases through material presenting considerable resistance. For example, in correcting the spacing it would be necessary to shift the toe of the pile or fixed member and this shifting would be very difficult if not impossible where the fixed member enters the ground or bottom to a considerable depth or passes through sandstone or other interfering material. In work of this kind as heretofore carried out it has been the practice to use blocks of uniform length. Obviously, in the event that the spacing is not uniform, the blocks will be too long for some of the intervals and too short for others.

An important object of the invention is to provide a method of building a wall of this general type whereby such difficulties will be avoided.

Another important object is to provide a novel and advantageous wall of the general type referred to above.

A further object is to provide a method of wall building in which the blocks are cast in situ between successive fixed members, to assure the proper lengths for the blocks.

Another object is to provide a wall which will automatically adjust itself to changes in the level of material at the bottom of the wall.

According to a preferred form of carrying out the above objects of the invention a plurality of reinforced concrete piles having plane lateral faces parallel to their axes are

arranged parallel to each other at intervals along the line of the proposed wall, and fixed in position in the ground or in the bottom of a body of water. Such vertical piles, being parallel to each other and having their plane lateral faces parallel to their axes, are adapted to serve as guides for blocks or wall sections located therebetween. The wall sections are preferably cast in the intervals between the piles and are therefore of the proper length. Each of these sections or blocks is shaped within a form of which the adjacent portions, substantially the halves, of the surfaces of the two adjacent piles constitute a part and serve to form grooves in the otherwise plane ends of the blocks. The spaces between the fixed members or piles is thus practically closed and a relatively tight joint assured.

In order to enable the blocks thus formed to be lowered or to adjust themselves to their effective positions, either bonding must be prevented or bonds formed between contacting faces of the piles and blocks must be broken. The desired conditions in this respect may follow as a result of natural shrinking of the members, prior lubrication of contacting faces, separation by force, or prior covering of contacting faces. In walls of any considerable length, provision is made for expansion joints which may involve the use of sheet packing, such as building paper placed between the sections.

According to one form of carrying out the pile construction features of the invention, the pile is formed of a suitable core, such as an I-beam, a jetting tube arranged between flanges of the I-beam, flexible metal material (such as a cable) wound around the core, and cementitious material around the core and flexible material and having plane lateral faces with their common edges parallel to the axis of the beam or core. The concrete at the lower end of the pile is made pointed and preferably is of pyramidal form having as many lateral faces as the pile proper. Preferably the core or I-beam extends upwardly above the concrete and such projecting portion is provided with means, such as a hole in the middle line of the central

web of the I-beam, for suspending the pile vertically or in plumb.

The form for making the pile is preferably assembled from two right-angled angle irons 5 which make the form of the same cross section throughout substantially its whole length, and is held together in any suitable manner as by clamps, the point being formed in any suitable manner as by a device of proper 10 shape clamped between the lower ends of the angle irons. Vents are provided at intervals along the form so as to permit air and water to flow therefrom as the concrete is poured with the form in inclined position 15 with the air vents up, each vent being sealed as soon as the portion of the form below the same is filled.

With these and other objects in view, the 20 present invention resides in certain novel features of the wall and wall elements and the method of making such elements, which can best be described in connection with the accompanying drawings, in which:

Figure 1 is a longitudinal section of the 25 form taken along the transverse diagonal plane separating the two angle iron sections;

Fig. 2 is a view in elevation of the assembled form;

Fig. 3 is a top plan view of the complete 30 form;

Fig. 4 is a transverse sectional view of the form at one of the vents;

Fig. 5 is a sectional view taken along the line 5—5 of Fig. 8;

Fig. 6 is a perspective view of a block constituting half of the closure at the upper end 35 of the form;

Fig. 7 is a perspective view of an end member of a form for casting a block;

Fig. 8 is a top plan view illustrating the connection of the I-beam cores of successive 40 piles;

Fig. 9 is a top plan view, partly in section, taken along the line 9—9 of Fig. 10;

Fig. 10 is a view in elevation, partly in section, taken along the line 10—10 of Fig. 9;

Fig. 11 is a sectional view, taken along the line 11—11 of Fig. 9;

Fig. 12 is a perspective view illustrating 50 the manner of supporting a completed block or wall element during the removal of the form and the lowering of the block into position;

Fig. 13 is a top plan view of a completed 55 wall, and

Fig. 14 is a view in elevation illustrating the completed wall of Fig. 13 extending out from the shore line.

Referring to the drawings, 20 designates 60 a pile embodying a preferred form of the invention and including a core 21 in the form of an I-beam of sufficient strength to sustain the bending stresses to which the pile is to be subjected, a jetting tube 22 extending 65 from one end of the pile to the other at one

side of the main web of the beam and between the corresponding flanges, additional concrete-holding and reinforcing means such as metal cable 23 wound helically around the beam and secured at the ends in any suitable manner, and cementitious material or concrete 24 around the core, the jetting tube and the additional reinforcing means serving to give the proper contour at the outer surface of the pile.

The pile also has a reduced or sharpened lower end to facilitate setting or driving and preferably this is produced by tapering the concrete at the lower end of the pile uniformly, by means to be described herein-after, from a point slightly above the lower end of the beam to a relatively sharp tip at a point below such end of the beam. In order that the pile may conveniently be held vertically or in plumb, particularly for sinking by a jet of water supplied through the tube 22, the I-beam 21 is provided at its upper end with an opening or hole 25 centrally positioned in the main web of the beam.

One important use of the piles of the present invention is that of guiding into and holding in position wall members such as blocks or panels, located between successive piles and combining therewith to form a complete wall. It is particularly important, 95 therefore, to have the lateral surface of each pile cylindrical, that is, generated by a straight line moving parallel to itself and to the axis of the pile or, in the preferred form, to the core or I-beam. The cross section of the body of the pile may take different forms but preferably it is in the general form of a regular polygon, such as a square, and the lateral surface of the pile is made up of a corresponding number of 100 plane surfaces.

The formation of the cementitious material such as concrete around the core and other elements may be effected in different ways but preferably by use of form sections adapted to fit together along longitudinal lines. When the pile is of suitable cross section, it is desirable to build up the form from a plurality of angle iron members of suitable length and strength. In making a pile of square cross section such as illustrated in the drawings, use may be made of angle irons 26, each having webs of equal width and positioned at a right angle to or perpendicular to each other. These angle irons are of standard form and may easily be obtained, and preferably they have machined plane surfaces.

These angle irons are placed together, as illustrated in Figs. 3 and 4, and are then firmly secured together in any suitable manner as by a suitable number of clamps 27. As illustrated, each of these clamps includes two clamping members 28 recessed or notched to receive substantially one-half of the angle iron body of the form and suitable means, 125

such as threaded rods or bolts 29 passing through the members 28 at opposite sides of the angle iron body and nuts 30 threaded on said bolts 29, to force the members 28 together and clamp the angle irons firmly.

The form may also include a point former for the piles adapted to be clamped between the angle irons by the lower clamp 27. The point former may consist of one or a plurality of sections 31 and preferably is shaped at its interior to produce a pyramidal tip having the same number of lateral faces as the body of the pile. Preferably the form is provided with venting means and, as illustrated in Figs. 2 and 4, this may be in the form of bores 32, at the edge of an angle iron, which may be closed by suitable devices, such as screw plugs 33 cooperating with internal screw threads in said bores.

In making a pile, the form is assembled if not already in that condition; the jet pipe or tube 22 is placed in position with reference to the core or I-beam 21; the cable 23 is wound helically around the I-beam and jet pipe and its ends secured in any suitable manner as by passing them between the I-beam and coils of the cable intermediate its ends; the assembled core, jet tube and cable are inserted in the form in proper position; and concrete or other suitable material is poured into the form while it is supported in inclined position with the vents or bores 32 at the upper side thereof. Each vent serves in succession from the lowest one up, to vent excess water and air and each one is closed by one of the screw plugs 33 as soon as the concrete filling reaches that point. The form may be closed at the top by blocks or closure members 34 (Fig. 6) each adapted to fit in one of the angle irons on one side of the I-beam and having grooves 35 to receive the flanges of the beam and a surface 36 set back from the edge surfaces 37 to allow for half of the thickness of the main web of the I-beam.

One of these closure members may be in the form during the filling operation and the other inserted later, both being retained until the concrete is suitably set. When the form is removed from the pile the end of the I-beam will project from the concrete. After the concrete is set, the pile may be removed from the form as by knocking down or disassembling the latter, the pile being cured as desired. In order to prevent the concrete of the pile from sticking to the form and therefore acting to resist separation and to injure the surface of the pile, the angle irons or members may be covered in advance of the casting operation with any suitable material, preferably building paper or the like, to prevent such sticking.

As illustrated in Figs. 9 to 14 inclusive, 40 denotes blocks or wall sections of which walls embodying a preferred form of the present invention are built in connection with fixed

members or piles, preferably such as piles 20 hereinbefore described, arranged at suitable intervals along the line of the wall and parallel to each other. This condition of parallelism is essential in order to obtain proper guiding action for the blocks and to permit automatic adjustment of the latter in case material is displaced beneath the same. Preferably the piles are set vertically. After placing the piles in alignment and with the openings 25 in the upper ends of the I-beams substantially in alignment, a careful adjustment of the piles in parallelism may be effected, as illustrated in Fig. 9, by suitable means, such as a series of rods 41, which may, for convenience, be of different lengths. As shown in Fig. 9 a rod 41 is placed with its screw-threaded ends extending through the openings in the upper ends of the I-beams in two successive piles, and the upper ends of the I-beams are drawn together by means of nuts 42 engaging the outer sides of the webs of the I-beams. It will be evident that nuts might also be used at the inner surfaces of said webs. Inasmuch as the rod 41, shown in Fig. 9, is of greater length than the distance between the I-beams, the rods used in connecting these I-beams with the I-beams in the piles at opposite sides of the two shown in this figure are arranged to be connected with the first mentioned rod 41 by means of turn-buckles 43, and these rods may be connected at their other ends with the corresponding I-beams by means of nuts as illustrated for the first mentioned rod 41.

After such adjustment of the piles in parallelism the blocks 40 are cast therebetween substantially in situ, but ordinarily above the positions which they will ultimately assume, a preferred form for casting such a block being illustrated in Figs. 9, 10 and 11. When working on land above high water mark the form when placed about two piles ordinarily rests on the sand, but when working off shore and above high water, the form is supported above the water in any suitable manner, for example, by stringers 44 carried by posts 45 set in the sand or other material, or the forms may be supported by the piles.

Preferably each form includes a plurality of beams or members 45a extending across the stringers 44 and serving to support the floor members or planks 47 which extend across all of the beams and to opposite sides of the piles 20 between which the block or wall section is to be cast. It will be seen that in the middle line of the form the ends of the planks must be shaped to fit against the corresponding piles and are limited in length to the distance between the corresponding parts of the piles.

Each end of the form includes upright planks or members 48 resting on the floor members 47 and arranged in each case on opposite sides of a pile so that substantially

one-half of the pile at its inner side or a suitable casing or spacing device thereon serves as a part of the structure defining the inner surface of the form, cross members 49 extending across the form in engagement at their centers with the outer edges of the piles and provided at opposite sides of the piles with projections 50 adapted to engage the outer surfaces of the upright members or planks 48 so as to hold the inner faces of the members 48 in the vertical plane passing diagonally through the corresponding pile, horizontally arranged members 51 placed one above another at the sides of the form, vertically arranged members 52 at opposite sides of the form in engagement with the side members 51, tie-rods 53 passing through the members 52 at their upper and lower ends and having at their opposite ends nuts 54 theaded thereon to engage the outer surfaces of the members 52 and draw the opposite ones together so as to hold the sides of the form firmly in position, upright end members 55 engaging the cross-members 49, and held together at their upper and lower ends by tie-rods 56 and nuts 57 threaded on the ends of said tie-rods. Although the forms have been described as supported on posts 45, it will be evident that the stringers 44 may be supported on the upper ends of the piles by transverse members 58 each engaging the upper end of a pile and connected by means of tie-rods 59 and nuts 60 threaded on the ends thereof with the stringers.

After the form has been assembled in any position it is lined, particularly at its ends, by suitable material, such as sheet packing 61. The sheet packing at the ends forms casings covering the surfaces of the piles and conforming to the shape thereof. Preferably the sheet packing has both faces of irregular conformation with elevations and depressions and when the concrete or other material is poured or caused to flow into the form, it will force the packing against the plane surfaces of the pile and will enter the depressions at the surface of the packing with which it contacts, so that the face of the block conforms with the face of the packing and when the finished block is lowered along the piles the concrete will carry the packing therewith. At the outer faces of the packing the elevations alone will contact with the piles and the surface of the packing at the depressions will be out of contact with the piles. Friction of the faces will thus be reduced and relative movement between the pile and the packing will be facilitated by reason of the reduced area of contact and also by reason of the depressions in the packing forming spaces of refuge for the material abraded from the high spots during such relative movement and also forming places of refuge for material from slight imperfections and slight irregularities in the respective

faces, including the substantially plane face of the pile, which imperfections and irregularities might otherwise interfere with the relative movement of the faces by causing them to bind. It should be understood that the packing is applied at the sides and bottom of the forms as well as the ends, insuring a watertight form by covering the joints of the form. 70

In order to remove the bottom of the form after a block 40 has been cast therein, it is necessary to support the newly formed block during the removal of the floor members, and such support may be furnished in any suitable manner as by a cable or cables 62 placed across the floor members of the form beneath the packing and passing downwardly between the outer edges of the floor and the lower members at the sides of the form. The sides of the form may be removed by loosening the nuts 54 on the tie-rods 53 and then the cable or cables 62 may be brought up around the sides of the block as shown in Fig. 12 and the block supported in any suitable manner as by a suitable derrick or crane. Then the form may be disassembled or knocked down to as great an extent as necessary and shifted to another position. 75

It will be obvious that after a form has been filled with concrete that the concrete will have to stand for a certain length of time to set properly. When the forms are, as in the present case, intended to be set up at the shore and over the water in some cases, it is desirable and often necessary to cover the top of the form to keep out the water and spray from the waves during the setting period. As illustrated in Figure 11 the concrete may be covered by a plurality of planks or members 63. The concrete may be protected in any other suitable manner as by sheets of building paper. 80

When it is found desirable or necessary to construct a very strong wall, the tops of the I-beams 21 of the piles may be connected with substantial rigidity by suitable means such as I-beams 64 bolted or riveted thereto as indicated in Figures 5 and 8. Inasmuch as the blocks are kept separate from each other and from the piles by suitable means such as sheets of packing material, as already described, the blocks or wall sections 40 adjust themselves in accordance with the supporting material beneath the same, and the upper surfaces of the blocks or the surfaces of the upper row of blocks would not be in the same horizontal plane. The present invention contemplates however the provision of a wall with a uniform coping formed by concrete surrounding the I-beams 64 and extending down into a groove 65 formed in the tops of the wall members or blocks at the upper edge of the wall. With this construction there may be considerable settling of the blocks without separation thereof from the coping. 85 90 95 100 105 110 115 120 125 130

66 formed by the I-beams 64 and the concrete cast therearound. A convenient way of forming the grooves 65 in the upper parts of the blocks 40 is illustrated in Figs. 9 and 11
 5 which illustrate a form for the groove 65, including a bottom 67 extending between the two piles 20 and sides 68 extending from end to end of the main form at the outer limits of the two piles at the end of said main form.
 10 Thus when the main form is filled with concrete, the concrete will be held back from the groove space 55 by a similar form including the bottom 67 and the side 68. Later the bottom 67 and sides 68 of the grooved form may
 15 be removed and the concrete coping cast around the I-beams 64 so as to fit in the groove 65 of the upper blocks, being separated from the concrete of the blocks by suitable means such as packing paper.
 20 The sections or blocks 40 are of considerable size and weight, for example, each block may weight ten tons. The weight of the blocks may, however, vary in accordance with the pressure of the water or waves to be sustained. As a matter of fact the wall of the present invention takes a form in which the blocks are so heavy that they alone form a wall of which the parts are very difficult to displace.
 25
 30 It should be understood that the structure of the blocks may be varied in different ways, for example, at the end of a wall one block or a plurality of superposed blocks may be formed around a pile but separated therefrom by suitable means such as a casing or spacing means of packing material or paper. The lower block at the outer end of the wall in Fig. 14 is of this form. In some instances it may be found desirable to form the blocks
 35 of lower rows of greater width than the blocks of higher rows thus giving a broader footing and greater stability. It may also in some cases be desirable to form hollow blocks which may be handled more easily
 40 and when in final position may be filled with concrete thus forming a solid block. The packing material applied at the ends of the forms and which adheres to the ends of the blocks serves not only to assure a slip joint
 45 connection between the blocks and the piles and between successive blocks but also to provide an expansion joint effect. It will be evident that, in the preferred form of wall, it is of very great importance to make the end faces of the blocks as nearly as possible plane faces and adjacent faces as nearly parallel as possible, and also the piles as straight as possible; inasmuch as otherwise the blocks would not slide properly along the piles and along each other. It is, however, only necessary that there be at least one straight or plane face, the other face may be irregular.
 50 It will be obvious to those skilled in the art that various changes may be made within the scope and spirit of the present invention.

tion and of the present claims, and accordingly the invention is not limited in the respects specifically described herein, and illustrated in the drawings. For example, the blocks or wall members may be cast around the guiding members or piles and may engage each other between the piles, the blocks being spaced from the piles by suitable spacing means having such engagement with the piles as to assure a stop connection therebetween.
 70
 75 Having thus described my invention, I claim:
 1. The method of building a concrete wall, which includes fixing a plurality of parallel members in vertical alignment, forming concrete blocks between upper portions of successive parallel members so as to fit therebetween and extend laterally at each side of each of said parallel members in plane surfaces lying in a common plane passing substantially through the axis of such member, and lowering each of such members until it adjusts itself in engagement with material beneath the same.
 80
 85

2. The method of building a concrete wall, which includes fixing a plurality of parallel piles in vertical alignment, providing forms between upper portions of successive piles to cast blocks of greater thickness than the piles and of length substantially that of the distance between the axes of the two piles but having at its ends grooves receiving substantially half of the adjacent portions of the piles, filling said forms with concrete to form blocks, supporting each block independently of the corresponding form, and disassembling the form to permit lowering of such supported block to adjust itself in position.
 90
 95

3. The method of building a concrete wall, which includes fixing a plurality of parallel piles in vertical alignment, providing forms between upper portion of successive piles to cast blocks of greater thickness than the piles and of length substantially that of the distance between the axes of the two piles but having at its ends grooves receiving substantially half of the adjacent portions of the piles, placing a sheet of packing material across each end of each form, filling said forms with concrete to form blocks faced with said sheets of packing, supporting each block independently of the corresponding form, and removing the form to permit lowering of such supported block into engagement with material adapted to support the same.
 100
 105
 110

4. The method of building a concrete wall which includes fixing a plurality of parallel members in vertical alignment, said members having substantially straight plane faces, and casting concrete blocks between and against such faces of successive parallel members so as to fit therebetween and be slid able thereon, whereby said blocks may be allowed to adjust
 115
 120
 125
 130

themselves automatically with respect to the material beneath the same.

5. The method of building a concrete wall which includes fixing a plurality of concrete members in vertical alignment, said members having substantially plane faces and casting concrete blocks between and against such faces of parallel members so as to fit therebetween and be slidable thereon, all of said blocks extending laterally on each side of said parallel members in planes parallel to the axes thereof, whereby said blocks may be allowed to adjust themselves automatically with respect to the material beneath the same.

10 6. The method of building a concrete wall which includes fixing a plurality of parallel members in vertical alignment, said members having substantially straight plane faces and casting concrete blocks between and against such faces of successive parallel members so as to fit therebetween and be slidable thereon in close relation to the face of adjacent blocks all of said blocks extending laterally at each side of said parallel members with plane surfaces lying in a common plane passing substantially through the axes of such members, whereby said blocks may be allowed to adjust themselves automatically with respect to the material beneath the same.

15 7. The method of building a concrete wall which includes fixing a plurality of parallel members in vertical alignment, said members having substantially straight plane faces, placing a layer of packing material in contact with such faces and casting concrete blocks between and against the packing layers of successive parallel members so as to fit therebetween and be slidable thereon, whereby said blocks may be allowed to adjust themselves automatically with respect to the material beneath the same.

20 8. The method of building a concrete wall which includes fixing a plurality of parallel members in vertical alignment, said members having substantially straight plane faces, placing layers of packing material in contact with the faces of said members and casting concrete blocks between and against the packing layers of successive parallel members so as to fit therebetween and be slidable thereon, all of said blocks extending laterally on each side of said parallel members in planes parallel to the axes thereof whereby said blocks may be allowed to adjust themselves automatically with respect to the material beneath the same.

25 9. The method of building a concrete wall which includes fixing a plurality of parallel members in vertical alignment, said members having substantially straight plane faces, placing layers of packing material in contact with said faces and casting concrete blocks between the packing layers of successive parallel members so as to be slidable thereon in close relation to the faces of adjacent blocks,

all of said blocks extending laterally on each side of said parallel members with plane surfaces lying in a common plane passing substantially through the axes of such members, whereby said blocks may be allowed to adjust themselves automatically with respect to the material beneath the same.
